SCRUBBING ATTACHMENT FOR PORTABLE
VACUUM-TYPE FLOOR SWEEPERS

Merrill H. Terry, Columbus, Ohio

Application March 1, 1941, Serial No. 381,350

2 Claims. (Cl. 15—4)

This invention relates to a floor covering scrubbing attachment for motor driven, vacuum-type, floor sweepers, the general object of the invention being to provide improved means for effecting the removal of dirt and soil traces from textile floor coverings so that the latter may be maintained in a more cleanly and visually attractive condition than is now obtainable with conventional cleaning facilities.

The vacuum-type floor sweeper, now so widely used in removing loose dirt particles from woven floor coverings, is highly efficient and easy to operate. However, floor coverings collect solid particles or compounds of a nature which the ordinary vacuum sweeper does not remove. Such solids often consist of coal or carbon deposits or films which adhere tenaciously to the nap of floor carpets or rugs, cannot be removed by the vacuum or beater action of vacuum floor sweepers, and detract from the natural lustrous color which floor coverings bear when newly laid. In order to remove these adhering deposits, it is now an accepted practice to send the rugs or carpets to cleaning establishments having scrubbing facilities for renovating said coverings. This necessitates the removal of the rugs or carpets from the floors on which they are normally placed, the loss of their use while being cleaned and the costs involved.

In accordance with the present invention, a vacuum sweeper of the motor driven type is provided, one preferably having motor-driven brush or beater, with a tank for the reception of a cleansing fluid and, also, provided at the forward portion of the sweeper head or casing is a fluid distributor, the fluid being conducted from the tank to the distributor by means of a valved conduit, whereby in the operation of the sweeper so constructed, the cleansing fluid is distributed under controlled flow upon the nap of the woven floor covering, and by the operation of the motor driven brush or beater, the cleansing solution is driven into the fibers of the floor covering to remove adhering soil films or deposits, any excess moisture being removed from the floor covering by the operation of the motor driven fan or blower of the sweeper.

Another object of the invention resides in the provision of a collector or water trap which is adapted for attachment to the air outlet of the fan housing of a vacuum sweeper equipped with the aforesaid attachment means, the said trap or collector being employed in lieu of the usual dust collecting bag of the sweeper.

Other objects of the invention reside in an attachment of the character set forth which is capable of being readily applied to standard makes of vacuum floor sweepers, simple and convenient to install on said sweepers, convenient to operate and inexpensive to manufacture.

In the single embodiment of the invention disclosed in the accompanying drawing:

Fig. 1 is a perspective view of a vacuum-type floor sweeper provided with the scrubbing attachment forming the present invention;

Fig. 2 is a view mainly in vertical section taken through the sweeper and the associated scrubbing attachment;

Fig. 3 is a bottom plan view of the sweeper and the cleansing fluid distributor of the attachment;

Fig. 4 is an enlarged vertical transverse sectional view taken through the distributor.

Referring more particularly to the drawing, the numeral 1 designates a vacuum type floor sweeper. While the sweeper may be of varied construction, the form illustrated comprises a casing 2 having formed therein a fan chamber 3 and a communicating open-bottomed brush or beater chamber 4. Mounted on the top of the 15 casing 2 is the usual electric motor 5, and the shaft of this motor is connected with a rotatable fan or blower 6 disposed horizontally in the chamber 3. Also, the lower end of the motor shaft carries a pulley 7, over which is trained a 20 belt 8, the latter being employed to transmit rotary motion from the motor shaft to a revoluble brush or beater 9, mounted in the casing chamber 4. This brush or beater member may be of the type having bristles 37 and have spirally 25 arranged rubber beater blades 38. The rotatable element is of such diameter that it projects through the open bottom of the chamber 4 in order to directly contact with the upper surfaces or nap of woven floor covering, such as rugs or 30 carpets. The casing is supported by the usual 35 rollers 36.

In operation, the brush or beater dislodges dust or dirt particles contained on or in the fibers of the floor covering, and by the suction 40 produced through the operation of the fan or blower 6, the dust or dirt is discharged through an outlet 10, leading from the back side of the casing 2, and delivered into a bag or other receptacle, not shown, for collection purposes. The 45 casing 2 carries the usual pivoted or swinging handle 11, by means of which the sweeper may be propelled in a convenient, manually executed manner across the floor covering.

In connection with a sweeper of this general 50 type, the present invention provides a scrubbing attachment for removing solid matter from the floor covering which, under normal conditions, cannot be successfully attacked by a standard floor sweeper. While the mechanism forming the present invention is referred to as an attachment for floor sweepers, it will be understood that the same may be manufactured into the construction of a floor sweeper of the type disclosed to form an integral or unitary part 55 thereof.

In the particular embodiment of the invention selected for illustration, the mechanism comprises a cleansing fluid distributor 12. This distributor includes a conduit 13, suitably perforated at intervals along the bottom thereof, as indicated at 14. Surrounding the conduit 13 is an open-bottomed hood 15, which is of approximately the same length as the conduit 13 terminated immediately adjacent to nap 16 of a fabric floor covering 17. The back of the hood 15 is provided with a plurality of attaching clips 18. Each of these clips is formed with a vertical depending leg 19, spaced from the back wall of the hood 15. The legs 19 of these clips are received between an elastic bumper strip 20 and the forward wall of the casing 2. By this means, the distributor may be quickly and securely attached to the front of the vacuum sweeper.

Leading from the central portion of the conduit 13 is a length of hose 21, which is flexible in order to provide for the necessary swinging movement of the sweeper handle 11. The upper end of the hose 21 is connected with a control valve 22, which is fastened with the lower end of a cleansing fluid-containing tank 23. This tank is secured longitudinally on the lower portions of the handle 11, and may be detachably held in connection with said handle by means of friction exerting clamps 24. Any suitable cleansing fluid may be retained within the tank 23, preferably a soap solution, although other fluids may be used either in combination with the soap solution or separately, such as rug-brightening compounds, or moth or insect propagation inhibitors.

Preferably, the upper portion of the tank contains a manually actuated air pump 25, so that the fluid within the tank may be placed under pressure for positive delivery to the distributor. In addition, the control valve 22 is provided with an actuating crank 26, the outer end of which is connected with a wire or cable 27, leading to a pivoted trigger 28 mounted on the upper end of the handle 11. By finger operation of the trigger, a supply of fluid flowing to the distributor may be readily controlled.

It has also been found advantageous to mount upon the lower side of the conduit 13 of the distributor a fine gauze or wire screen 29. The use of this screen enables the cleansing fluid to be readily and uniformly distributed on the floor covering throughout the full length of the conduit, providing for an even application of the cleansing solution.

While the attachment may be used with a standard dust-collecting bag of the type found on most vacuum sweepers, a water collector or trap 30 is preferably employed in connection with the outlet 10 of the casing 2. The forward end of this collector or trap is provided with flanges 31 which match with corresponding flanges 32 provided as standard construction on vacuum sweepers. When the regular dust bag has been removed, the flanges 31 may be registered with the flanges 32 and united therewith by means of the usual threaded fasteners 33. At its top, the trap 30 is formed with a hinged frame 34 having a foraminated covering 35. Thus water or moisture will be collected in the trap 30 and removed after a given cleaning operation, or from time to time during a prolonged operation.

In view of the foregoing, it will be seen that the present invention provides a simple and readily applied cleansing attachment for conventional vacuum-type floor sweepers. The construction of the attachment is such that it may be quickly

and conveniently applied to or removed from an associated sweeper. When removed from the sweeper, the latter may be used in its normal intended manner. However, at intervals when woven floor coverings become dull in appearance because of the presence thereon of soil deposits, which are not removed by the ordinary operation of the sweeper, the use of the attachment comprising the present invention is indicated. During such use, the collecting bag of the sweeper is removed and the trap 30 substituted. The tank 23, filled with the cleansing fluid, is then clamped to the handle 11, and the distributor head fastened to the front edge of the casing 2 by the use of the clips 18, or their equivalent, the wire cable 27 being connected with the trigger 28 and the valve arm 26. The sweeper is then used in the ordinary manner, the motor 5 causing the rotation of the fan 6 and the brush or beater 8. By opening the valve 22, the cleansing fluid is advanced under pressure from the tank 23 to the conduit 13, passing through the perforations 14 in said conduit and the special screen 29 onto the nap of the floor covering. By the action of the rotatable brush or beater, the cleansing fluid is driven into intimate contact with the soil-containing fibers of the floor covering, dissolving the soil deposits and effecting their positive removal from the covering. The soil-containing moisture is then removed from the floor and advanced through the casing 2 by the action of the fan or blower 6, being finally deposited in the trap 30. The sweeper with the attachment is advanced over the floor covering with about the same amount of manual energy as when the cleaning attachment is not used. The attachment, when employed, enables rugs or carpets to be cleaned while on the floor and without removal and when so employed, restores to the floor covering its normal bright lustrous appearance.

As illustrated in Fig. 4, the lower edge of the front wall of the distributor hood 15 is equipped with a row of bristles 39 which assist in elevating and separating the nap fibers prior to the application of the cleaning compound thereto.

What is claimed is:

1. A solution applying attachment for vacuum-type floor cleaners comprising a container for reception of the solution, means for removably attaching said container to the floor cleaner, a perforated distributing head, conduit means establishing communication between said container and said head, a foraminated shield carried by said head to facilitate the distribution of solution discharged therefrom, hood means partially surrounding said head and secured thereto, and means for separably connecting said hood to a vacuum cleaner casing with the lower edges of said hood in closely spaced relation to the floor covering on which said cleaner is positioned.

2. Floor-scrubbing attachment mechanism for vacuum-type floor cleaners having a casing adaptable to be movable over a floor surface by a propelling handle, said casing having a resilient bumper strip applied to its outer surfaces, the improvements comprising a container for the reception of a scrubbing solution mounted on said handle, an open-bottomed solution-distributing head adapted for application to the front of the casing, conduit means extending from said container to said head, and a plurality of hook devices formed with said head and engageable with said bumper strip to maintain said head detachably applied to the front of said casing.

MERRILL H. TERRY.
